UNITED STATES PATENT OFFICE.

JEFFREY T. FERRES, OF RICHFORD, VERMONT.

MACHINE FOR MAKING VENEER DISHES.

SPECIFICATION forming part of Letters Patent No. 364,404, dated June 7, 1887.

Application filed September 17, 1884. Serial No. 143,273. (No model.)

To all whom it may concern:

Be it known that I, JEFFREY T. FERRES, residing at Richford, in the county of Franklin and State of Vermont, have invented certain Improvements in Machines for Making Veneer Dishes, of which the following description, in connection with the accompanying two sheets of drawings, constitutes a specification.

10 This invention relates to automatic means for pressing and folding a previously cut and scored or creased veneer-blank into the form of a dish or tray, and also of forming, driving, and clinching a wire staple or fastener at each 15 end thereof to confine and bind together the upturned flaps which constitute the ends of said dish, as well as devices for feeding to the machine the veneer-blanks and discharging the finished dish therefrom.

20 The machine embodying my improvements is shown in the accompanying drawings, wherein—

Figure 1 gives an elevation of that side of my machine from which the product is discharged. 25 In this view a part of the feeding apparatus and a portion of the under forming-die are not shown in order to bring into view more clearly parts immediately in their rear. Fig. 2 is a view, partly in elevation and partly in 30 transverse vertical section, on line 1 2 3 of Fig. 1, of my machine. Fig. 3 is a side elevation of sprocket-wheel, pawl and ratchet, and rack and pinion for operating feeding apparatus. Fig. 4 is an edge view of same. Fig. 35 5 is a top or plan view of the devices for bending down or clinching the wire staples which fasten the folded flaps constituting the end of the dish. Fig. 6 is a longitudinal vertical section taken through the center of the 40 staple-forming dies. Figs. 7, 8, and 9 are views of different positions of the dies or slides in process of forming and driving a staple. Fig. 10 shows a veneer-blank for a dish before same has been folded. Fig. 11 is a view of a 45 finished dish. Fig. 12 is a view of the end-folders, showing their relative positions in regard to the folding-bed and to the dish.

The machine may be resolved into the following groups of mechanism—viz:

50 First. Devices for feeding the dish-blanks to the machine and discharging the finished

product therefrom, the same apparatus being employed for both purposes.

Second. Mechanism for folding the veneer or other dish blank and holding same while 55 the fastening-staple is being driven.

Third. Apparatus for feeding to the staple-forming machinery the wire from which the staples are made. Inasmuch as any well-known method or apparatus for doing this 60 part of the work may be employed in this machine, I have not shown the same, it being understood, without further explanation, that any such suitable apparatus may be employed therewith.

Fourth. The staple forming and driving devices, which are consolidated.

Fifth. Devices for clinching or bending down the prongs of the staples after they are driven.

Sixth. The driving mechanism for operating 70 these several parts.

The mechanism is all mounted in or on the frame A and receives its motion from main driving-shaft B, upon which the driving-pulley A' and friction-cone C are mounted. Pinion N drives gear O on shaft P. On shaft P is placed the crank-disk C, which carries the pin i and cylinder Q, upon the surface of which the friction-rolls c c and d d are pivoted. Said friction-rolls impart an intermittent semi-rotary reciprocating motion to shafts f f by alternately engaging lugs e e on opposite sides, whereby the clinching-disks g g at top ends of shafts f f are brought to bear on the prongs of the inserted staple and bend 85 them down.

The crank-pin i on disk C works in a transverse slot or way, D, on the vertical slide-rod E. In Fig. 1 of the drawings I have shown only the central and right-hand portions of 90 my machine; but both sides are alike in construction, there being two sets of staple-forming devices and two slide-rods E. Each of the slide-rods is provided with a section of rack R, which engages with a sectoral gear, S", 95 having a radial arm, S, which connects with and actuates the pitman T, whereby the staple forming and driving devices are operated. A cross-head, F, is attached to the upper ends of slide-rods E, and to this cross-head is attached the plunger W, which engages with and actuates the staple-wire-severing punch 100

X. It is also provided with the bridge G, which, together with cross-head F, affords guideways for the drive-rods I I. To the lower ends of said rods I I are attached the 5 two folding devices or shapers L and M. These folders act in conjunction with the sectional folding-beds D' D', which are bolted to girt E' of the frame of the machine.

I will now describe the independent action 10 of each group of operative devices without reference to the concurrent action of any other group, taking up the feeding apparatus first. This consists of two sprocket-wheels, K' K', disposed one on each side of the machine. 15 Over the sprocket-wheels runs the chain L', which at regular intervals is equipped with feeding-fingers N' N'. Motion is imparted to the sprocket-wheels by means of a rack, E', and pinion F' on the sprocket-shaft G', Figs. 20 3 and 4. Gear F' and ratchet H' are rigidly attached to shaft G', and pawl J', pivoted on an arm of the sprocket-wheel, engages with ratchet H'. The sprocket-wheel runs loosely in one direction on shaft G'. Rack E' is attached to a bracket-arm, D', projecting from cross-head F, and takes a corresponding vertical reciprocating movement therefrom. The motion of cross-head F through the connections above described imparts an intermittent 25 progressive motion to the feed-chain, in the direction of the arrow, of about the breadth of one dish-blank, or of the interval between two adjacent feed-fingers, N' N'. The blanks are fed to the machine by laying them on platform O' just behind and against the finger carrying in the last blank and in position for the next following finger to catch it and carry it forward under the folding-die M. The chain remains stationary while the dish is 30 shaped, and when the upward movement of the cross-head carries the folder M up clear of the dish the advancing finger N' forces the dish off from the form D' onto the table P', or onto any receptacle provided therefor, at the 35 same time the following finger N' carries a fresh dish-blank into position between the folding-dies, to be manipulated as above described.

The mechanism for folding the blank and 40 shaping the dish consists of a bottom die or folding-bed divided into two parts or halves, so as to leave a clear and unobstructed interval between them for the passage of the feed-chain. These sectional beds are shown at D' 45 D', and are bolted permanently to some part of the frame of the machine. Their tops are made to conform to the interior shape of the end of the completed dish. Together they constitute the male member, as it were, of a 50 pair of dies, of which the folding-die M is the female member. Die M has two drive-rods attached to its upper side, which pass up through guideways or bearings in the cross-head. For the sake of clearer discrimination, 55 I have termed the die M the "side-folder," and that portion of the apparatus which bends down the central end fold (shown at L) the

"end-folder." Drive-rods I I pass through and freely play in apertures in end-folder L. Folder L has a tongue at each end bent 70 down to an angle to conform to the shape of the finished dish, and also has two steady-pins, b b, attached to its under side, which pass through folder M, so as to bear on the dish-blank. The bottom ends of the lips of the 75 end-folder are slightly longer than the steady-pins, so as to permit the central flap of the dish-blank to be first broken down or bent over the forming-bed and seat itself in its true position to be bent before the steady-pins 80 strike it and confine it to the forming-bed. The side-folder M does the duty of bending down the portions of the blank which form the sides of the dish p p, Fig. 10, and also the corner-sections n n n n, which overlap the center 85 flaps, o o, in the finished dish. These offices are accomplished, respectively, by the side folding-lips, ll, and the corner lips, kk, Fig. 12.

To regulate the co operative action of the two folders L and M, the drive-rods I I are 90 equipped with collars a a, nuts J J, and springs H H and K K. The springs H H, interposed between collars a a and bridge G, act to force the rods I I down until their further descent is arrested by the stop-nuts J J. The springs 95 K K, interposed between the under side of cross-head F and the upper side of folder L, act to force folder L down until it rests on the top of the bosses r r of folder M. The action of these springs is such that when the cross-head F is elevated to its greatest limit the lips j j will be depressed, so that their lowest extremities will be first to engage the dish-blank by striking the center flaps, o o, of the blank when the descending movement commences. 100 105

The wire for forming the fastening-staples is supplied to the staple-forming dies by any convenient or suitable feeding device through the orifice s, Fig. 1. The staple-forming dies consist, mainly, of two horizontal plates or 110 slides, both of which have an endwise movement in the direction of the driving of the staple. They are arranged to slide one on top of the other, and are mounted in pairs, one on either side of the machine, on a suitable table, 115 Q'. The details of these slides are shown in Figs. 6, 7, 8, and 9, and their driving-connections in Fig. 1. The case in which the slides work consists of a bed-piece, Q'', and a cap-piece, Y'. These are fastened together, and also to table Q' of the machine. Between the 120 two plates are fitted the two slides R' and S'. Slide S' is fitted to work in a longitudinal seat or way constructed in top of slide R'. Top slide, S', receives a positive reciprocating movement through pitman T, Fig. 1, from the arm S of the sectoral lever S'', which is pivoted on the bracket Y and takes its movement from the slide-rod E through the rack and segment R S''. The slide R' has a subsidiary movement imparted to it from pitman T, through the impact of the shoulders a'' a' at the outer end thereof, against washers or collars u or t, which are loosely fitted on pitman U. Between 125 130

these collars is interposed a coil-spring, V, whose office is to maintain proper relative longitudinal adjustment between slides R' and S' during the process of forming the staple.

5 b'' b' represent pins set in the rod U and adapted to bear against the outer faces of the collars t u. These pins are set in such position that the pin b' is pressed against by the washer t in the downward movement of the pitman T and the pin b'' is pressed against by the washer u in the upward movement of the pitman.

To the front end of slide S' is hinged the lip V', which has a transverse upturned ledge, w, 15 at its outer end. When slide S' is thrown forward or inwardly a sufficient distance, lip V' will drop down, as seen in Fig. 6, and when it is retracted lip V' will impinge against the beveled end e' of bed-plate Q'', and thereby be 20 forced into a horizontal position, as seen in Figs. 7 and 8.

When lip V' is dropped, as seen in Fig. 6, it leaves the hinge-chucks d' d' projecting, as well as the central part, e', of slide S', so that 25 such projecting sections d' d' and e' form the hammer or driver for forcing the prongs of the staple through the folded flaps of the end of the dish when the parts are in the position seen in Fig. 1.

30 The staple is formed by first passing the wire through guide s under cutter X, Fig. 1, (which cutter works in die X', Fig. 9,) and cutting off a proper length thereof to form a staple. This blank y then drops through hopper T' down 35 onto and athwart the lip V' in position, as in Fig. 7, between ledge w and tongues c'' c''. In the back-stroke of the slides the movement of the slide R' is arrested or retarded by its rear end impinging against a lug or abutment, d'', cast 40 on bed-piece Q'', before slide S' has reached the limit of its stroke, thus causing lip V' to be still further retracted between tongues c'' c'', and thereby causing blank y to be caught between ledge w and tongues c'' c'' and the ends thereof 45 to be bent around so as to lie in creases x x, being bent into the form shown in Fig. 8. After being so bent the sliding movement is reversed, and the slide S', advancing ahead of slide R', permits lip V' to fall down or drop 50 into a dependent perpendicular position out of the way of striking against the side of the former-bed D', as in Fig. 1. The slide S' is caused to advance ahead of the slide R', inasmuch as the spring V has to be compressed by 55 the shoulder a'' on pitman T striking the collar u before the slide R' can be moved. The completed staple then is held by its prongs in creases x x of the tongues c'' c'', with the driving end of slide S' following closely in its 60 rear. Slide R' advances until the tongues c'' c'' strike against the end of the dish, when its movement is arrested; but slide S' still advances and forces the prongs of the staple through the folded flaps of the end of the dish 65 and into the position seen in Fig. 5, ready to be bent down or clinched.

The clinching devices are shown in elevation

in Fig. 1 and in plan in Fig. 5. They consist of four vertical shafts arranged in pairs, one pair for each half of the forming-bed. These 70 shafts are shown at f f and are supported in suitable bearings. One of each pair has a tappet-lug, e, at its bottom end, which is acted upon by the friction-rolls c c and d d on drum Q, the leading set c c acting against one wing of 75 the tappet-lug to rotate the clinching-heads g'' g'' in one direction and the trailing set d d acting against the opposite wing of said tappet-lug to effect a reversal of said clinching-heads. The construction and operation of said 80 clinching-heads may be deduced from Fig. 5. The heads g'' g'' have each a portion of their periphery cut away, so as to leave a shoulder, n' n'. These shoulders are shown in repose, or in position to be acted on by the advance of leading friction rolls c c. As cylinder Q rotates, it first brings rolls c c into engagement with tappet-lug e, thereby causing a partial rotation of the clinching-heads against the prongs of the staple as they protrude through the apertures in the side of the forming-bed D', and 90 bends them down toward each other on the inside of the dish. This being accomplished, the trailing friction-rolls d d come up, and, impinging against the opposite side of tappet-lug e, rotate the clinching-heads in the opposite direction and restore them to their first position, ready to act upon the next staple to 95 be driven.

The operation of the machine is as follows: 100 Cross-head F being elevated, a blank is laid on the feeding-table and the machine started. The feed-chain carries the blank between the folding-dies, and the further descent of the cross-head carries folder L down to a point 105 where the extremities of folding-tongues j j bend down center flaps, o o, of the blank, and at this point steady pins b b pin the blank firmly down and arrest further descent of folder L. Pending this, plunger W, acting on 110 punch X, has severed a staple-blank from the feed-wire and the same has dropped into hopper T' preparatory to formation into a staple by the back-stroke of the staple-forming slides. Further descent of cross-head F carries holder 115 M down to its work, and the sides p p and corner flaps n n n are folded down into position. At this stage the slides S' and R' carry staple y up into position to be driven through the 120 folded end flaps of the dish at either end of the folding-bed D' D', and further advance of slide S' drives the staple prongs through the overlapped flaps, as shown in Fig. 5. This being accomplished, the clinching of the prongs 125 under the action of the clinching disks or gears g'' g'', controlled by friction-rolls c c and d d, follows, as hereinbefore described. This completes the formation of the dish, when the up-stroke of the cross-head and slide-rods E effects the discharge of the dish by the movement of chain L', at the same time, through the back-throw of the sectoral arm S, causing a 130 reversed movement of slides R' and S', whereby the last staple-blank cut off is, through the

co-operative action of said slides, formed into a staple, as before stated.

Hence I claim—

1. In a machine for making a folded dish of the kind described, a forming-bed consisting of two semi-sections having an open way between them, as a provision for facilitating the delivery of the dish-blank to the folding-dies and the discharge of the folded or finished dish from the machine, substantially as specified.
2. The described member of the staple-forming device which performs the duplex function of bending the prongs of the staple in its back-stroke and of driving the staple in its direct or forward stroke, consisting of slide S', having hinged lip V', with ledge w, all constructed and arranged to operate substantially in the manner described, and for the purposes set forth.
3. The combination of the stationary forming-bed divided, as shown, with the endless-chain feeding device having an intermittent movement, substantially as described.
4. The combination of slides R' and S', with the spring V interposed between them, sub-

stantially as shown, and collars u and t, connected with slide R', and shoulders a'' and a⁴, connected with slide S', substantially as specified.

5. The combination of end-folder L, having tongues T⁴, and pins b b, with the divided folding-bed, substantially as described and set forth.

6. The combination of slide R', having elevated lateral ledges and driving-channels x x, with driving-slide S', provided with the hinged lip V', in the manner described, and for the purposes specified.

7. The combination of drum Q, carrying tappet-wheels c c and d d, with the shafts f f, carrying tappet-lugs e e, and clinching-heads g'' g'', recessed to form the shoulders n', and for the purposes set forth.

In testimony whereof I have hereunto subscribed my name, at Richford, Vermont, this 27th day of August, A. D. 1884.

JEFFREY T. FERRES.

In presence of—

SILAS P. CARPENTER,
A. S. BAKER.
